S. Z. GIBSON

HAIR CLIPPER

Filed March 13, 1922

Inventor
SIMON Z. GIBSON

By Attorney
Richard J. Cook

UNITED STATES PATENT OFFICE.

SYMON Z. GIBSON, OF SEATTLE, WASHINGTON, ASSIGNOR OF ONE-HALF TO J. C. GALLAGHER, OF SEATTLE, WASHINGTON.

HAIR CLIPPER.

Application filed March 13, 1922. Serial No. 543,344.

To all whom it may concern:

Be it known that I, SYMON Z. GIBSON, a citizen of the United States, and a resident of Seattle, county of King, and State of Washington, have invented certain new and useful Improvements in Hair Clippers, of which the following is a specification.

This invention relates to improvements in hair clippers, and more particularly to clippers of that character that are to be mechanically driven, such as by means of a flexible shaft that may extend to the clippers from an electric motor or other mechanical driving mechanism.

15 It is an object of this invention to improve upon clippers of that character as heretofore constructed by the provision of certain gearing and operating mechanism whereby there is less frictional heat generated, vibrating is 20 reduced and a more efficient and longer wearing device is produced.

Other objects of the invention reside in the details of construction of the various parts and in their combination and mode of 25 operation.

In accomplishing these and other objects of the invention, I have provided the improved details of construction, the preferred forms of which are illustrated in the accompanying drawings, wherein—

Figure 1 is a central, longitudinal, sectional view of clippers constructed according to the present invention.

Figure 2 is a plan view of the same, with 35 the cover plates removed to show the driving gearing.

Figure 3 is a transverse, sectional view taken on the line 3—3 of Figure 1.

Figure 4 is a transverse, sectional view on 40 the line 4—4 of Figure 1.

Figure 5 is a perspective view of the clippers.

Referring more in detail to the drawings—

45 1 designates the housing of the device taken as a whole. This consists, preferably of a metal plate, bent in the form of a handle, as is best shown in Figures 1 and 2, and which has upwardly turned opposite side flanges 2 and 3 and an end wall 4, over which is fitted a cover plate 5 which is held in place by means of screws extended therethrough at its ends.

50 Fixed to the lower end of the housing is the base cutter shoe 6 having cutting teeth

7 along its forward edge. A movable cutter plate 8 is slidably mounted upon the base shoe and is held in position thereon by means of lugs 9 on its under side which are 60 slidable within grooves 10 transversely of the base shoe, and by means of the forward edge of a cap, or cover 11, which is fitted over the cutter and lower end of the housing.

The means provided for holding these 65 parts assembled, comprises two screws 12 and 13 that are extended upwardly through the base shoe, at opposite sides adjacent its back edge, through the lower forward edge of the housing and are fixed at their ends 70 in a cross bar 14. A bolt 15 is extended upwardly through this bar at its center and through an aperture in the rearward edge of the cap, and a nut 16 is tightened on the bolt against the cap to hold the parts securely 75 together.

The means for operating the movable cutter blade consists of mechanism contained within the hollow handle portion of the device. There is a driving shaft 17 entering 80 the casing at its outer end. It is intended that this shaft be connected, in any suitable manner, to an electrically driven, or mechanically driven flexible shaft. The inner end of this shaft 17 is supported within a 85 transverse wall 18 about midway of the housing, and adjacent this end a worm gear 19 is fixed thereon which operates in mesh with and drives a gear wheel 20 mounted on a stud 21 that is fixed in the base of the 90 housing. Formed on the upper face of the gear 20, is a bevel gear 22 which drives a bevel gear 23 on the end of a shaft 24 that extends through the wall 18 and is rotatably fixed in two spaced apart posts 25 and 26 95 formed on, or fixed to, the base of the housing. Fixed on this shaft 24, between the said posts, is an eccentric 27 about which one end of a pitman, or connecting rod 28 is mounted; the other end of the rod being 100 fixed pivotally to a cross head 29 that is slidable along two parallel rods 30 and 31 which are fixed at their opposite ends in the side wall 2 and posts 25 and 26.

To the cross head 29 is pivotally connected one end of a link 32 which has its other end likewise attached to the upper end of a blade oscillating lever 33. This lever is pivotally mounted at about its longitudinal center on a screw 34, which extends through 105

110 the base cutter shoe 6 having cutting teeth

the lower end of the cover plate and into a boss 35 in the base plate, and at its forward end the lever has a rounded head 36 that is operatively fitted within a slot 37 in 5 the cutter 8.

Assuming that the parts are so constructed and assembled, it is apparent that when the shaft 17 is driven, the shaft 24 will likewise be driven through the connecting gears 10 19, 20 22 and 23, and this causes rotation of the cam 27 and reciprocal movement of the cross head 29 on bars 30 and 31 accordingly. This effects oscillation of the lever 33 through the connection of the link 32 15 and a resultant operation of the cutter blade 8.

In this construction the casing is made oil tight and by so doing the gears may be kept running in oil and well lubricated.

20 It is also desired to place a thumb guide 40 on the side of the housing to make use of the device easier.

A clipper so constructed requires less

power, than is necessary to operate most clippers now in use, and the construction 25 and mode of operation eliminates, to a great extent, the vibration and heat that usually is generated.

Having thus described my invention, what I claim as new therein and desire to secure 30 by Letters Patent, is:

In a hair clipping device of the class described, a transmission mechanism comprising a lever pivotally mounted at a point between its ends and adapted to be operatively connected at its outer end to actuate a cutter blade, a driving shaft having an eccentric journal, a pair of guide rods, a cross-head slidable on said rods, a link connecting the cross-head with the inner end of the blade actuating lever, a pitman having one end mounted on the eccentric and connected at its other end with the cross-head.

Signed at Seattle, Washington this 7th day of March 1922.

SYMON Z. GIBSON.
